UNITED STATES PATENT OFFICE

151,822

DESIGN FOR A JUICER

Oscar E. Hammers, Chicago, Ill.

Application December 27, 1946, Serial No. 135,793

Term of patent 14 years

(Cl. D44—29)

To all whom it may concern:

Be it known that I, Oscar E. Hammers, a citizen of the United States, residing at 7229 Summerville Avenue, in the city of Chicago, county of Cook, and State of Illinois, have invented a new, original, and ornamental Design for a Juicer, of which the following is a specification, reference being had to the accompanying drawings, forming a part thereof.

Fig. 1 is a perspective view of the juicer, showing my new design.

Fig. 2 is a plan view of the juicer.

Fig. 3 is a side elevational view of the juicer, and

Fig. 4 is a front elevational view of the juicer.

I claim:

The ornamental design for a juicer, as shown.

OSCAR E. HAMMERS.
